His Attorney.

UNITED STATES PATENT OFFICE.

GEORGE S. HUNT, OF CHICAGO, ILLINOIS.

MOLD.

Application filed November 16, 1923. Serial No. 675,108.

To all whom it may concern:

Be it known that I, GEORGE S. HUNT, a citizen of the United States, and a resident of the city of Chicago, county of Cook, and State of Illinois, have invented certain new and useful Improvements in Molds, of which the following is a specification.

My invention relates to improvements in molds, especially adapted for forming tomb stones out of concrete material such as sand and cement, the object of the invention being to provide a simple and durable construction of this character by means of which certain metal emblems or other ornamentation may be readily incorporated in and made a permanent part of the tomb stone or other object formed in the mold.

Other objects will appear hereinafter.

The invention consists in the combinations and arrangements of parts hereinafter described and claimed.

The invention will be best understood by reference to the accompanying drawing forming a part of this specification, and in which—

Fig. 1 is a vertical section of a mold embodying the invention, said section being taken substantially on line 1 of Fig. 2;

Fig. 2, a horizontal section of the mold taken on line 2—2 of Fig. 1; and

Fig. 3, an enlarged, partial, transverse section taken through the bottom of the mold.

The preferred form of construction, as illustrated in the drawing, comprises a mold made of four wooden sides, 4, 5, 6 and 7 hinged together at the four corners as shown, one of the hinged connections being detachable so that the said sides may be readily swung downwardly to free a block enclosed therein. The bottom 8 of the mold is detachably secured to the sides thereof by means of dowels 9 as shown. Arranged centrally in the bottom of the mold is a recess 10, the edges 11 of said recess being flared, said recess being arranged and adapted to receive portions of a metallic emblem or other ornamental plate 12, the edges of which are flared to correspond with the flare in said recess.

By this arrangement it will be observed that when the mold is assembled and an emblem 12 positioned in the recess 10 the portions of said emblem of greatest lateral dimension protrude somewhat above the bottom 8 of the mold, so that when the block 13

is formed or cast in the mold the said emblem will be partially embedded and securely locked in said block by means of the flaring edges of the emblem. Thus when the block is removed from the mold the emblem will also be readily removed and will be securely attached to and permanently incorporated in the block. The mold is especially adapted for forming tomb stones with suitable emblems or other metallic plates or ornamentation secured to and permanently incorporated therein.

While I have illustrated and described the preferred form of construction for carrying my invention into effect, this is capable of variation and modification without departing from the spirit of the invention. I, therefore, do not wish to be limited to the precise details of construction set forth, but desire to avail myself of such variations and modifications as come within the scope of the appended claims.

Having described my invention, what I claim as new and desire to secure by Letters Patent is:

1. A mold comprising sides and a bottom, said bottom being recessed to receive portions of a metallic member having projection above the bottom between the sides of the mold, substantially as described.

2. A mold comprising sides and a bottom, said bottom being recessed to receive portions of a metallic member having projection above the bottom between the sides of the mold, the sides of said recess being flared, substantially as described.

3. A mold comprising sides and a bottom, said sides being connected at the corners, one connection being detachable, said bottom being recessed to receive portions of a metallic member having projection above the bottom between the sides of the mold, substantially as described.

4. A mold comprising sides and a bottom, said sides being connected at the corners, one connection being detachable, said bottom being recessed to receive portions of a metallic member having projection above the bottom between the sides of the mold, the sides of said recess being flared, substantially as described.

5. A mold comprising four sides and a bottom, said sides being connected at the corners, one connection being detachable,

and said bottom being detachably secured to said sides by means of dowels, said bottom being centrally recessed to receive portions of a metallic member having projection 5 above the bottom between the sides of the mold, the sides of said recess being flared, substantially as described.

In testimony whereof I have signed my name to this specification in the presence of two subscribing witnesses.

GEORGE S. HUNT.
